UNITED STATES PATENT OFFICE.

CHARLES CLARK, OF NEW YORK, N. Y., ASSIGNOR, BY DIRECT AND MESNE ASSIGNMENTS, TO CAP-HOLD, INCORPORATED, OF NEW YORK, N. Y., A CORPORATION OF NEW YORK.

CAP-RETAINER FOR DEFORMABLE TUBES, &c.

1,210,599.

Specification of Letters Patent.

Patented Jan. 2, 1917.

Application filed August 27, 1915. Serial No. 47,586.

To all whom it may concern:

Be it known that I, CHARLES CLARK, a citizen of the United States, residing in the borough of Manhattan of the city of New York, in the county of New York, in the State of New York, have invented certain new and useful Improvements in Cap-
10 Retainers for Deformable Tubes, &c., of which the following is a specification, reference being had to the accompanying drawings, which form a part thereof.

The use of deformable tubes and similar receptacles for the dispensing of toilet lotions has greatly increased recently and the favor with which they have been received by the public has led the manufacturers to make every effort to meet every objection, no matter how slight, to their use. As will be appreciated, these tubes are most widely used around basins or other bath fixtures where there is running water and it has been found, as is natural, that the relatively small cap which is threaded on to the neck of the tube is apt to slip from the fingers of the user and drop into the trap from where it may be carried out through the drain or may become lodged in such a position as to be unrecoverable and, at the same time, a serious obstruction 20 to the drain. Again, even if the cap does not drop into a trap, it remains a constant source of annoyance to the user as it must be handled with some care or it will slip from the fingers and perhaps roll along the floor to somewhat inaccessible places from which it can often be recovered only by the exercise of great agility. Not only has the liability to loss and the annoyance incidental to the dropping of the cap made it necessary for some means to be employed to overcome these objections, but the first principles of hygiene require that the cap should be protected against contact with the floor, drain and other places where it might pick up dirt or bacteria dangerous to health. It has been proposed to secure the cap directly to the neck of deformable tubes, etc., by means of a hinge-joint but this construction is unsatisfactory because of its prohibitive 40 expense and because the hinge-joint becomes clogged with the contents of the tube. This construction has a further objection that the contents of the tube are not held against leakage as it has been found necessary to

employ a screw cap to insure a tight connection around the lip of the neck. It has been proposed by others to enlarge the caps of these deformable tubes to a point where they cannot, by reason of their bulk, slip through the ordinary trap in the drain of a basin. 60 Obviously, this expedient entails a very considerable expense through the provision of additional metal and fails to meet the primary objection inasmuch as it does not prevent the cap from being dropped by the 65 user.

The present invention has for its object to overcome the difficulties pointed out above and to afford a practical solution of the problem by providing a retainer for the 70 caps of deformable tubes which shall be inexpensive, shall be readily applicable to any cap of any tube and shall possess the function of cleaning the threads on the neck of the tube whenever the cap is removed or 75 replaced whereby the contents of the tube are prevented from clogging on the neck and the cap is made to screw on and off at all times without difficulty.

In accordance with the invention the cap 80 has secured thereto a coil of wire or band which encircles the same and is pinched thereon and this coil or band has an eye through which passes another coil of wire or band which is passed around the neck 85 of the tube and rests snugly within the threads thereof so that this last named coil can be threaded on and off the neck in much the same manner that the cap is threaded on and off. The two coils or bands described 90 are loosely interconnected through the eye referred to so that when the cap is removed from the neck it is permitted to hang freely from the coil or band on the neck and preferably at such a distance from the neck that 95 it may be pressed out of the path of the contents of the tube when the latter are discharged, as by a tooth brush, shaving brush, etc. By the construction described, it will be understood that rotation of the band or 100 coil on the neck along the threads thereof, whenever the cap is removed or replaced, serves to clean the threads and remove all paste or the like therefrom and thereby facilitate the subsequent removal or re- 105 placement of the cap.

Other features of the invention will appear in connection with the detailed de-

scription of the accompanying drawings in which are illustrated several embodiments of the invention.

In the drawings Figure 1 is a view in elevation of a portion of a deformable tube on which is threaded a cap provided with a retainer constructed in accordance with the present invention. Fig. 2 is a view similar to Fig. 1, but showing the cap removed. Fig. 3 is a view similar to Fig. 1, but showing a slightly different form of retainer. Fig. 4 is a detail view of an integral coil of wire constituting one part of the retainer shown in Fig. 3. Fig. 5 is a view showing still another form of retainer. Fig. 6 is a detail view of one part of the retainer shown in Fig. 5. Fig. 7 is a view showing another form of retainer in which a band is used instead of a coil of wire. Fig. 8 is a detail view of the band shown in Fig. 7.

In Figs. 1 and 2 a deformable tube A, of usual construction, has secured thereon a threaded neck a through which the contents of the tube are discharged by pressure on the walls of the tube, as will be understood, and on which is threaded a cap b for the purpose of effecting a liquid tight closure of the neck. The improved retainer has, as one of its features, the adaptability of application to deformable vessels of any usual construction, so that the character of the vessels themselves need not be changed but the improved retainer may be applied readily to all vessels which any manufacturer may have in stock. Of course, in practice, the improved retainers will usually be applied at the time the vessels are manufactured, thereby saving a separate handling thereof. In the embodiment illustrated in Figs. 1 and 2, the retainer comprises two portions, one of which is formed as a coil of wire c which is passed snugly around the cap b and twisted adjacent its middle to form an eye c' and at its ends to press against the cap, as at c''. The other part of the improved retainer is formed by passing a wire d through the eye c' and twisting the wire so as to form therein an eye d' and then passing the wire snugly around the threaded neck a and twisting the free ends, as at d'', so as to maintain the wire in snug engagement with the neck. When the cap b is in position, the coil d is threaded down on the neck with the cap so as to lie in the very bottom-most thread and when the cap is unscrewed, the coil d rotates with the cap and is threaded along the threads of the neck until the cap is released and assumes the position indicated in Fig. 2. By reason of this movement of the wires c and d with the cap b, the threads of the neck are thoroughly cleaned whenever the cap is removed or replaced so that it becomes impos-

sible for the pasty contents of the vessel to clog and harden around the neck, as is usual in vessels of this character. As soon as the cap is released from the neck it is permitted to drop freely by reason of the loose engagement of the wires c d through the eyes c' d'. These eyes are formed at such distance from the cap and neck, respectively, as to permit the cap to remain suspended at an appreciable distance from the neck so that it will not interfere with the free discharge of materials and, indeed, may be pushed aside by a tooth brush, shaving brush, etc.

In Figs. 3 and 4 there is illustrated a slightly different form of retainer in which the interengaging coils of wire C D have their ends welded so as to form two separate integral coils of wire which are intended to be pressed on to the cap b and fitted on to the neck of the vessel A, at the time when the latter is manufactured.

In Figs. 5 and 6 there is shown a somewhat different form of retainer in which the coils of wire C' D' are neither integral, respectively, nor twisted at their free ends, but, on the contrary, have their free ends open so that the encircling coils are formed somewhat as eyes. This construction may be more satisfactory under some circumstances.

In Figs. 7 and 8 there is illustrated what is probably a more slightly form of retainer, in which the coils e f are formed as integral bands of metal intended to be pressed around the cap B and the neck a' of the vessel A', respectively, and engaged with each other by eyes e' and f'. In this form, the metal bands are maintained in fixed shape by means of small metal straps g passed around them between the eyes e' f' and the coils e f, respectively.

In each of the modified constructions illustrated in Figs. 3-8, the retainers are affixed to the neck of the vessel and the cap in exactly the manner described with respect to Figs. 1 and 2 and the operation in each instance is the same so that all of the advantages pointed out with respect to the embodiment shown in Figs. 1 and 2 are common to the remaining forms of retainers.

It will be evident to those skilled in the art, especially after considering the problem which this invention is intended to meet, that retainers of the same general character as those illustrated but of different construction mechanically, may be employed to advantage without departing from the scope of the invention provided such modifications fall within the terms of the appended claims.

I claim as my invention:—

1. In combination with a vessel having a threaded neck and a threaded cap therefor, a retainer for the cap comprising a band

encircling the neck of the vessel and loosely engaging the threads thereof below the cap, and a link secured to the cap to be non-rotatable with relation thereto and engaged 5 loosely by the band whereby rotation of the cap causes rotation of the link and rotation of the band along the threads.

2. A retainer for the threaded cap of a vessel comprising a band secured to the cap 10 to be non-rotatable with relation thereto, and another band encircling the neck of the vessel and loosely engaging the threads thereof below the cap, said bands having a pivotal engagement with each other where-

by rotation of the cap causes rotation of 15 both bands.

3. A retainer for the threaded cap of a vessel comprising a band secured to the cap to be non-rotatable with relation thereto, and another band encircling the neck of the 20 vessel and loosely engaging the threads thereof below the cap, said bands having interengaging eyes formed therein respectively whereby rotation of the cap causes rotation of both of said bands. 25

This specification signed this 24th day of August A. D., 1915.

CHARLES CLARK.
